DESIGN FOR A COMBINATION VANITY AND HEARING AID CASE

Christian A. Wolf, Van Nuys, Calif.

Application June 22, 1940, Serial No. 93,179

Term of patent 7 years

To all whom it may concern:

Be it known that I, Christian A. Wolf, a citizen of the United States, residing at Van Nuys, in the county of Los Angeles and State of California, have invented a new, original, and ornamental Design for a Combination Vanity and Hearing Aid Case, of which the following is a specification, reference being had to the accompanying drawing, forming part thereof.

Fig. 1 is a perspective view of a combination

vanity and hearing aid case showing my new design, with the vanity portion in open position;

Fig. 2 is a perspective view thereof, with the hearing aid portion in open position; and

Fig. 3 is a perspective view thereof, in closed position on a slightly smaller scale.

I claim:

The ornamental design for a combination vanity and hearing aid case, as shown.

CHRISTIAN A. WOLF.
